The ornamental design for a beverage server, as shown and described.

DESCRIPTION

FIG. 1 is a perspective view of a beverage server showing our new design;

FIG. 2 is a right side elevational view thereof, which is a mirror image of the left side elevational view thereof;

FIG. 3 is a rear elevational view thereof;

FIG. 4 is a front elevational view thereof;

FIG. 5 is a top plan view thereof; and,

FIG. 6 is a bottom plan view thereof.

The broken lines showing portions of the beverage server are for the purpose of illustrating environmental structure only and form no part of the claimed design.
